D. W. TAYLOR

SCREW PROPELLER

Filed Aug. 7, 1922

Inventor
David W. Taylor,

By Watson, Cox, Morse & Grindle

Attorney

UNITED STATES PATENT OFFICE.

DAVID W. TAYLOR, OF WASHINGTON, DISTRICT OF COLUMBIA.

SCREW PROPELLER.

Application filed August 7, 1922. Serial No. 580,318.

To all whom it may concern:

Be it known that I, DAVID W. TAYLOR, a citizen of the United States, and residing at Washington, District of Columbia, have 5 invented certain new and useful Improvements in Screw Propellers, of which the following is a specification.

My invention relates to screw propellers and is intended and adapted to secure 10 greater efficiency and propelling power for blades of a given width than has been possible with propellers heretofore used. It tends to prevent cavitation on the face of the blade near the leading edge and reduces it to a minimum. The preferred embodiment of the invention shown for purposes of illustration includes a blade in 15 which the leading portion of the back is helicoidal with the following portion rounded and in which the face and back at the leading edge make the smallest practicable angle with each other and in which the surface of the leading portion of the face of the blade from its leading edge 20 is slightly concave in section and of increasing pitch for a certain distance and is followed by a portion which is rounded or convex in section. The convex portion may terminate in advance of the following edge 25 and be followed by a portion straight in developed section. The novel and useful features of the invention will be more fully understood from the following description and claims taken with the accompanying drawings. 30

In the drawings:

Fig. 1 is a section of a known form of propeller blade on the lines of a cylinder concentric with the shaft axis showing it as 40 unrolled or expanded into one plane;

Fig. 2 is a similar section showing diagrammatically a small cavity upon the face of the blade at the leading edge and a small cavity on the back of the blade at the following edge such as would be produced by a certain speed;

Fig. 3 is a similar section diagrammatically showing large cavities on the face and back of the blade such as would be produced 50 by extremely high blade velocity;

Fig. 4 is a similar section of a blade embodying one form of my present invention showing in dotted lines the outline of the usual ogival type of blade with the same 55 final pitch; and

Fig. 5 is a view similar to that of Fig.

4 showing a blade embodying my invention in a somewhat different form.

In order that the functions and advantages of the present invention may be easily 60 and accurately understood, the effects and results produced by the commonly used form of propeller blades will be first referred to and explained:

In a screw propeller working in open 65 water, the forward thrust developed in action is approximately proportional to and measured by the sternward momentum impressed upon the water acted upon by the screw. To obtain a given thrust we may 70 impress a high sternward velocity upon a small quantity of water, or a low sternward velocity upon a correspondingly large quantity of water. In the latter case the 75 efficiency is greater since there is relatively less energy wasted in giving sternward velocity to the water acted upon. If there were no changes of pressure in the water acted upon by the propeller, the forward 80 thrust would be exactly proportional to the sternward momentum generated. In practice 85 there are some pressure changes, but for propellers working in open water this effect is secondary, and we need consider the propeller primarily only as an appliance for producing sternward momentum in the water it acts upon.

Fig. 1 is a section of a known form of propeller blade on the lines of a cylinder concentric with the shaft axis unrolled or 90 expanded into one plane upon which we are supposed to look down. AB is the line of the shaft or the fore and aft line. FEL is a section of the helicoidal driving face which develops into the straight line FEL. 95 The pitch of the helicoidal face of this particular propeller is 14' 3 $\frac{1}{2}$ ", and the diameter 15' 11".

The section shown is taken at two-thirds 100 the radius in the vicinity where a large proportion of the work of the propeller is done. The line LC shows the instantaneous direction of advance of the developed section for a slip of 25 per cent of the actual propeller. The line FDL is the section of the back of 105 the blade which is of the ogival type. FDL is for its major portion an arc of a circle of large radius, but close to the ends, as indicated, arcs of small radius are struck to connect L the leading edge, and F the following edge, with the main portions of the back. 110

Consider now what happens to the water

in the immediate vicinity of the blade as it passes, and assume first that the water originally at rest remains at rest until influenced by the blade section, and that what is known as cavitation is not present. The water which passes near the driving face LEF is diverted athwartships and astern, producing excess pressure on the face of the blade. This pressure is a maximum near the leading edge, and falls off near the following edge as the excess pressure gives velocity to the water, so that the water would leave the face with little final increase of pressure. The change of velocity is always astern.

Consider now the action upon the water of the back FDL. This forces its ways into the water at a much greater angle than the face, so that the actual parting of the water is not at the leading edge L, but at a point on the back behind L, though quite close to it, and at the actual leading edge there is a flow of water from front to back. The extreme leading portion of the blade back is evidently inclining forward rather than backward. Hence we have here sternward pressure or negative thrust on the blade and forward momentum given the water. This of course is highly conducive of inefficiency. But as the water passes further along the blade back, the pressure changes to suction, a corresponding sternward velocity is developed and the water leaves the back at the following edge F with a greater sternward velocity than the water leaving the face.

All of the above is, as stated, upon the assumption that what is known as cavitation is not present, and also that the water was at rest before being acted upon by the blade. Now in the case of an actual rotating propeller as contrasted with an ideal section advancing linearly, the water reached by a blade has been already influenced more or less by preceding blades, resulting mainly in a certain sternward velocity. The result is to render less abrupt the action of the leading portion of the face of the blade since the water already has a certain amount of the sternward velocity which the blade face is striving to impart. The action is substantially the same as if the edge L instead of advancing along the line LC, were advancing along a line corresponding to less slip, such as LC¹. When we consider the action of the back of the blade, it is obvious that the initial sternward velocity of the water due to action of preceding blades will intensify the negative thrust of the leading portion of the back of the blade and cause negative thrust over a larger portion of the back. Nevertheless, if there is time for the suction of the following portion of the back of the blade to fully influence the water, it will leave the blade much as before, so that notwithstanding the eccentricities and perturbations of

the action of the leading portion of the blade, the thrust is in the end little affected. The efficiency, however, is prejudicially affected since it calls for the application of greater force.

Suppose, however, the velocity of the blade through the water is steadily increased. We have seen that for such a blade as in Fig. 1 when in action, the water will be flowing around the leading edge from back to front. This water is curving and its pressure is reduced in proportion to its velocity. The pressure of the surrounding water, however, tends to force it back into contact with the blade face. As blade velocity increases, a time will ultimately come when the pressure of the surrounding water is not adequate to keep the water flowing around L from back to front in contact with the propeller face, and a cavity is formed over the leading portion of the face of the blade. If the cavity is small, the major portion of the face FEL acts upon the water much as before and the thrust is not much affected. But as velocity increases the cavity necessarily gets larger, and in the end the face of the propeller has little or no action upon the water.

Fig. 2 shows in a diagrammatic way a small cavity 10 upon the propeller face at the leading edge indicated in section. This cavity is of course prejudicial to efficiency, but would not radically reduce thrust and efficiency. Fig. 3 shows similarly a large cavity 11 corresponding to higher blade velocity. The cavity on the face such as shown in Fig. 3 is highly prejudicial to thrust and efficiency. I may remark here that it is generally believed, and for a long time I myself believed that these cavities contained air. I have found, however, by experiment that they are vacuous to a high degree.

Let us consider now what happens to the back of a propeller blade such as shown by section in Fig. 1 as its velocity through the water increases. The leading portion of the back forces the water forward with more and more velocity. The pressure of the adjacent water neutralizes this action and forces it back into contact with the following portions of the blade back until its limit is reached and it can no longer keep the water in contact with the following portions of the blade back. Then a cavity appears here. Fig. 2 shows in ideal form a small cavity 12 on the blade back at the following edge and Fig. 3 shows a large one 13.

Much experience has established that cavitation is very detrimental to the efficiency of propellers. The only palliative measure found of value so far is to make the propeller blades very wide and correspondingly thin. This makes the angle of entrance of the leading edge small and reduces the disturbances which coarse, blunt blades, such as shown in Fig. 1, produce.

Wide blades also give more time for the water pressures to bring the water back to contact with the front and rear faces and hence nullify the effects of cavitation near the leading edge. Disregarding cavitation, however, a wide blade is essentially less efficient and more expensive to manufacture than a blade of normal width. While an extra wide blade which does not cavitate is 10 more efficient than a blade of normal width that does cavitate, it is inferior to a blade of normal width that does not cavitate.

My invention consists in a novel form of blade section of normal width which is 15 more efficient than the extra wide blades of the commonly used forms and is less liable to cavitation particularly on the face of the blade where it is most harmful. Figures 4 and 5 show in full lines two blade sections 20 embodying my invention and a corresponding section of the usual ogival type having the same final pitch being shown in outline in dotted lines.

To avoid cavitation on the face of the 25 blade, it is important that the leading portion of the face shall be concave as shown at 14 and 15 in Figures 4 and 5 and that the leading portion of the back of a blade shall make a smaller angle with the line of 30 advance than the leading portion of the face of the blade. For structural reasons it is necessary that this concave portion shall be followed by a convex portion, but this must be relatively long and merge gently into the 35 hollow or concave portion and the following portion of uniform pitch, if any. The leading portion 16 of the back of the blade is helicoidal, i. e., straight in developed section at the extreme leading edge, and curves 40 gently into the usual round back 17. Its pitch is such that its inclination to the line of advance is as small as possible and preferably not over five degrees and, as above stated, its inclination to the line of advance 45 should not be greater than that of the leading portion of the face of the blade.

The leading portion of the face of the blade makes with the back the smallest angle practicable with the materials available 50 for construction, and the leading edge is sharp or rounded on the minimum radius practicable with the materials available for construction. Passing back on the face of the blade from the leading edge there is 55 first a portion which is hollow or concave in section, i. e., of increasing pitch followed by a portion which is rounded or convex in section, i. e., of decreasing pitch, and this convex portion may be followed by a portion straight in developed section extending to the following edge. In Fig. 4 the following convex or rounded portion 18 in developed section on the face of the blade extends to the following edge. In Fig. 5 the 60 convex portion 19 does not extend to the

following edge but at a point in advance of that edge merges into a face portion 20 which is helicoidal and straight in developed section and which extends to the following edge. 70

Having thus described my invention, what I claim as new and desire to secure by Letters Patent is:

1. A propeller blade in which the leading portion of the back is straight in developed section and the leading portion of the face is concave in developed section. 75

2. A propeller blade in which the leading portion of the back is straight in developed section and the leading portion of the face is concave in developed section, the angle between the faces at the leading edge being as small as practicable with the material used forming a sharp edge. 80

3. A propeller blade in which the leading portion of the back is helicoidal having such pitch that its inclination to the line of advance is not materially over five degrees and in which the leading portion of the face is concave in developed section. 85

4. A propeller blade in which the leading portion of the back is straight in developed section and the leading portion of the face is concave in developed section and of increasing pitch followed by a portion convex in developed section of decreasing pitch. 90

5. A propeller blade in which the leading portion of the face is concave in developed section to the edge and at the smallest practicable with the material used angle to the leading portion of the back. 100

6. A propeller blade in which the leading portion of the face is concave in developed section to the edge and at the smallest practicable with the material used angle to the leading portion of the back, the concave portion of the face being followed by a convex portion of decreasing pitch. 105

7. A propeller blade in which the leading portion of the back is straight in developed section gradually curving into rounded form which extends to the following edge, its pitch at the leading edge being such that its inclination to the line of advance is not materially greater than five degrees, and in which the leading portion of the face is concave in developed section and of increasing pitch. 110

8. A propeller blade in which the leading portion of the back is straight in developed section gradually curving into rounded form which extends to the following edge, its pitch at the leading edge being such that its angle of inclination to the line of advance is not materially greater than five degrees, and in which the leading portion of the face is concave in section and of increasing pitch followed by and merging with a portion convex in section and of decreasing pitch, the angle between the face and back at the lead- 115 120 125 130

ing edge being as small as practicable with the material used.

9. A propeller blade in which the leading portion of the back is straight in developed section and the leading portion of the face is concave in developed section, the leading portion of the back being at a smaller angle to the line of advance than the leading portion of the face.
10. A propeller blade in which the leading portion of the face is concave in developed section to the edge and at the smallest practicable with the material used angle to the

leading portion of the back, the concave portion of the face being followed by a convex 15 portion of decreasing pitch, and the convex portion by a portion straight in developed section extending to the following edge.

11. A propeller blade in which the leading portion of the back makes a smaller angle 20 with the line of advance than the leading portion of the face of the blade.

In testimony whereof I hereunto affix my signature.

DAVID W. TAYLOR.
